UNITED STATES PATENT OFFICE.

MILTON E. HELIN AND HENRY R. HAWKINSON, OF CHICAGO, ILLINOIS.

DEVICE FOR HOLDING OR LOCKING SANDPAPER ON THE ROLLS OF FLOOR-SURFACING MACHINES.

Application filed February 28, 1923. Serial No. 621,746.

To all whom it may concern:

Be it known that we, MILTON E. HELIN, a citizen of the United States, and HENRY R. HAWKINSON, a subject of the King of

5 Sweden, both residing at Chicago, in the county of Cook and State of Illinois, have jointly invented certain new and useful Improvements in Devices for Holding or Locking Sandpaper on the Rolls of Floor-Surfacing Machines, of which the following

10 is a specification.

This invention relates to improvements, generally speaking, in sand papering or floor surfacing machines, but has particular

15 relation to means employed for holding or locking a sheet of sand paper on the roll of such a machine, and it consists in certain peculiarities of the construction, novel arrangement and combination of the various

20 parts thereof as will be hereinafter more fully set forth and specifically claimed.

As is well known to those skilled in the art to which our invention pertains, the sheets of sand paper or abrading material 25 which are applied to the rollers of floor surfacing or dressing machines, soon become worn to such an extent that they must be frequently removed from the rollers and new ones placed thereon. This frequent removal and reapplication of the sheets of sand paper or abrasive material, requires considerable time and skill when the appliances for holding the sheets of paper on the rollers are of the type or construction 30 heretofore in general use, besides being tedious and unsatisfactory.

The principal object of our invention is to provide a very simple and inexpensive locking and holding device for sand paper 40 on a roller for sand papering or floor surfacing machine, by means of which sheets of sand paper or the like can be quickly secured in operative position on the roller and readily removed therefrom without the employment of undue skill.

Other objects and advantages of the invention will be disclosed in the following description and explanation.

The invention will be explained and more 50 readily understood when read in conjunction with the accompanying drawing which illustrates an embodiment of which the invention is susceptible, it being understood that various modifications may be resorted to without departing from the spirit of the

invention, so long as they fall within the scope of the appended claims forming a part hereof.

In the drawing,—

Fig. 1 is a view in side elevation of a 60 roller of a floor surfacing machine with a sheet of sand paper or abrasive material applied thereto and held in position by our improved device.

Fig. 2 is an end view thereof showing 65 about the positions of the device when the edges of the sand paper are being initially engaged therewith.

Fig. 3 is a fragmental view of the roller showing the positions of the device when the 70 sand paper is locked thereby on the roller.

Fig. 4 is a fragmental cross-sectional view showing the parts in similar positions to that shown in Fig. 3.

Fig. 5 is a longitudinally sectional view 75 taken on line 5—5 of Fig. 1 looking in the direction indicated by the arrows, and

Fig. 6 is a detached view of the paper clamping members of the device.

Like numerals of reference refer to corresponding parts throughout the different views of the drawing.

The roller on which the sand paper is mounted and securely held by our improved device, is indicated as a whole by the numeral 8 and may be of any suitable construction but in the present instance is shown as consisting of two cylindrical sections 9 and 10, which have at their adjacent ends overlapping portions 11 and 12 secured together by means of screws 13 seated in one of said overlapping portions and engaging the other one. The outer end of each of the sections 9 and 10 of the roller is provided with a head 14, each of which is by preference provided with an inwardly extended hub 15 in which the axle or shaft 16 of the roller is located. The roller is fixed to the shaft 16 by means of a pin 17 extended through suitable openings in one of the hubs 90 100 15 and a registering opening in said shaft.

In its periphery the hollow roller is provided with a diagonally disposed slot 18 which extends through each end of the roller and communicates with the cavity 105 thereof and is employed to permit the end portions of the sheet 19 of sand paper or abrasive material to be inserted into the roller and between the clamping members 110 of the locking device. Near the inner edge

of the slot 18 each of the heads 14 of the roller is provided with a circular opening 20, which openings provide bearings for the ends of the clamping members 21 and 22, which as is clearly shown in Fig. 6 of the drawing, are segmental in cross-section and when assembled or located in said bearings, are held slightly apart at one of the edges of their meeting surfaces by means 10 of a screw or projection 23 mounted on the straight face of one of the clamping members and having a head to contact with the straight face of the other clamping member, all of which will be clearly understood by 15 reference to Fig. 6 of the drawing.

This spacing member 23 is so located as to be out of the path of the sheet of sand paper when its ends are inserted in the slot 18 and between the clamping members 21 and 22 and to accomplish this, the said spacing member is located on and near one of the ends of the clamping member. As is clearly shown in Fig. 5, the portions of the clamping members 21 and 22 located in the bearing openings 20, are reduced and rounded so as to turn easily in said bearings. One of the clamping members, preferably the one indicated by the reference numeral 21, is provided at one of its ends with a longitudinal extension 24 which is angular in cross-section so as to be easily engaged by a wrench.

Mounted on the extension 24 so as to turn therewith, is a ratchet toothed plate or rack 25, the teeth of which are adapted to be engaged by a pawl 26 pivotally mounted on the head 14 of the roller adjacent said rack. This pawl is actuated by a spring 27 which engages at one of its ends the pawl 26 between its pivot and the rack 25, and is then coiled around the pivot of the pawl and has its other end secured to a pin or projection 28 on the head 14 of the roller adjacent the rack. By this arrangement it is manifest that by turning the clamping member 21 by means of a wrench applied to the extension 24, or otherwise, in the direction of the pawl, the hook thereof will pass over the ratchet teeth of the rack until sufficient turning movement of the clamping members to tighten the sand paper on the roller has been accomplished when it is obvious the pawl will engage the rack so as to lock and hold it in the proper position for maintaining the sand paper in close contact with the roller, it being understood that the end edges of the sheet of sand paper shall have been inserted through the slot 18 and into the space 29 between the clamping members 21 and 22 before the said members are turned, or while the parts are in about the positions shown in Fig. 2 of the drawing. The roller 8 is as usual, provided on its periphery with a lining 30 of felt, which may be secured to the roller by

means of screws 31 employed in the usual manner. The sheet of sand paper 19 is located on the outer surface of the felt lining and for the purpose of facilitating its ends to be inserted through the slot, has its side 70 edges near its ends inwardly inclined as shown at 32 in Fig. 5 of the drawing.

From the foregoing and by reference to the drawing, it will be readily understood and clearly seen that, assuming it is desired to place a sheet of sand paper on the peripheral lining 30 of the roller, and that the clamping members 21 and 22 are disposed in about the positions shown in Figs. 2 and 6 of the drawings, it is manifest that by placing a sheet of sand paper on the roller and inserting its ends into the slot 18, said ends will be guided thereby and enter the space 29 between the clamping members 21 and 22, when by forcing the ends of the sand paper into the lower part of said space they will be in position to be gripped by the clamping members, when by turning said members to about the positions shown in Figs. 3 and 4 of the drawing, the paper will be tightened on the roller and securely held in such position by reason of the engagement of the pawl 26 with the teeth of the rack 25 until it is desired to remove the sand paper for replacement, which may be done by releasing the pawl from the rack, when it is obvious the clamping members can be turned to their initial positions shown in Figs. 2 and 6 of the drawing.

While we have shown the slot 18 extended entirely through the ends of the roller, yet it is manifest that this is not absolutely essential, as the ends of the slot may terminate at about the inner surface of the heads of the roller or short thereof.

By reference to Fig. 6 of the drawing, it will be seen that the spacing member 23 on the member 22 is located nearer the upper edge of said member than its lower edge and that the spacing member is rounded. This location of the spacing member and its construction affords a teetering point or pivot between the members 21 and 22 to the end that said members, when positioned for receiving the ends of the sandpaper 19, will be more widely separated at their upper edges than their lower ones, as shown in Fig. 6, thus insuring easy and accurate insertion of the ends of the sandpaper. Besides, this construction and arrangement permits the lower edges of the members 21 and 22 to be separated by the insertion of the sandpaper there-between and when so positioned to be tightly clamped by said lower edges and with a biting effect when the member 21 is turned by means of a wrench applied to the extension 24, for it is apparent that as the spacing member 23 is located at one side of the axial line of said members, this result will be effected.

Having thus fully described our invention, what we claim as new and desire to secure by Letters Patent is—

1. In a device of the class described, the combination with a roller having a slot in its periphery and a bearing opening in each of its ends near said slot, of a pair of spaced clamping members journaled at their ends in said openings, said members having their adjacent surfaces straight, a spacing member supported by one of said clamping members and located in the space between said members for holding them at one of the edges of their straight surfaces apart, and means on one of said members for turning the pair of members.
2. In a device of the class described, the combination with a roller having a slot in its periphery and a bearing opening in each of its ends near said slot, of a pair of spaced clamping members journaled at their ends in said openings, said members having their adjacent surfaces straight, a spacing member supported by one of said clamping members and located in the space between said members for holding them at one of

the edges of their straight surfaces apart, means on one of said members for turning the pair of members, and means to lock them in their turned position.

30

3. In a device of the class described, the combination with a roller having a slot in its periphery and a bearing opening in each of its ends near said slot, of a pair of spaced clamping members journaled at their ends in said openings, said members being of segmental shape in cross-section and presenting their flat surfaces towards each other, a spacing member supported by one of said clamping members and located in the space between said members for holding them at one of the edges of their adjacent surfaces apart, a longitudinal extension on the end of one of said members adapted to be engaged by an instrument for turning said member, a rack mounted on said extension to turn therewith, and a spring actuated pawl pivotally mounted on one end of the roller for engagement with said rack.
